UNITED STATES PATENT OFFICE.

JAMES OMAR OAKLEY, OF MONTREAL, QUEBEC, CANADA, ASSIGNOR OF ONE-HALF
TO PAUL EMILE LALANNE, OF MONTREAL, CANADA.

CAR DOOR.

Application filed January 24, 1925. Serial No. 4,454.

To all whom it may concern:

Be it known that I, JAMES OMAR OAKLEY, a subject of the King of Great Britain, and residing at the city of Montreal, in the 5 Province of Quebec, in the Dominion of Canada, have invented a new and useful Car Door, of which the following is the specification.

The invention relates to a car door as described in the present specification and illustrated in the accompanying drawings that form part of the same.

The invention consists essentially of the novel features of construction pointed out broadly and specifically in the claims for novelty following a description containing an explanation in detail of an acceptable form of the invention.

The objects of the invention are to furnish a means whereby the losses due to the destruction of the doors in freight cars will be eliminated; to insure a convenient place for the doors so that they will always be ready for immediate use; to avoid waste of 25 grain and reduce the cost of labour in handling and general upkeep; to supply a door that will be easy to operate in closing and opening the doorways of the car; to prevent the grain from working under the door 30 when in its closed position; to allow the grain to come out in a steady stream without any hindrance; and, generally to provide car doors that will be cheap to manufacture, durable in construction and efficient 35 in use.

In the drawings, Figure 1 is a perspective view showing the door construction.

Figure 2 is a cross sectional view of a car body showing the doors in their closed position.

Figure 3 is a cross sectional view of a car body showing the doors in their opened position.

Figure 4 is a perspective view of a section 45 of the door showing the hinge connections of the boards.

Figure 5 is a sectional view of a channel post for the door frame.

Figure 6 is a detail of the lower portion 50 of the door showing the angle plate.

Figure 7 is a cross sectional view of the construction illustrated in Figure 6.

Figure 8 is a perspective detail of a locking dog fitted on the door post.

Figure 9 is a perspective detail of a locking dog fitted to the bracket.

Figure 10 is a sectional view of a portion of the door showing the hinge connection.

Like numerals of reference indicate corresponding parts in the various figures.

Referring to the drawings, the car 10 suitable for grain or other cargoes has the door openings in the side walls surrounded by the frames 11 and 12, said frames having the parallel door posts 12 on one side 65 and the parallel door posts 14 on the other.

The tracks 15 and 16 on the one side of the car partially close in the vertical recesses in the posts 13 and form guideways for the door and extend upwardly and are curved 70 at 17 and 18 and project across the car at sufficient distance from the ceiling to permit a door to slide along there on top, said tracks being supported from the ceiling by 75 the hangers 19.

The other side of the car similar tracks 20 and 21 partially close similar recesses in the door posts on that side and extend upwardly and turn in easy curves 22 and 23 and project across the car at a convenient 80 distance below the tracks 15 and 16 to permit the door on that side to run thereon, said tracks 20 and 21 are supported by the same hangers 19.

The door 24 is formed of the narrow 85 cross boards 25 in heavy slot form tongued and grooved into one another and joined by flexible vertical wires 26 spaced one from the other in the width of the door and having eyes 27 through which the screws 28 are 90 inserted in securing said wires to the boards 25, said wires having also the outstanding eyes 29 at the joints of the boards through which the hinge pins 30 are inserted.

The hinge pins 30 have double offsets 95 forming the angle ends 31 and 32 thereby accounting for the thickness of the boards in projecting the said angle ends into the vertical slots of the door posts behind the tracks 15 and 16. These angle ends forming the running gear of the door and sliding up to its place under the car ceiling.

The lower end of the door 24 is cut out to form a slot 33 which is lined by the metal angle bar 34 for convenience in prying the door to give it a start in the operation of opening.

The locking dog 35 is formed with the

V-shaped jaw 36 and is pivoted on the door post so as to engage the outer corner of the top board of the door and be locked to that position by sliding it on its pivot into a transverse section of a V-shaped slot 37. The longitudinal section of said slot permitting the loosening of the dog in the operations of opening the door.

The door is in its upward position held by the dog 38 pivotally secured to the bracket 39 rigid with the door frame and this dog is formed with the projecting finger 40 and stop 41 and curved on the side 42 below said stop so that on lifting said dog from behind the door in its upward position where it has been holding it against the stop at the end of the track the complete door will slide to its closed position and the boards run freely under this dog. On the other side of the car the door is shown in two sections 43 and 44 which may or may not be used that way and the illustration is merely to explain how readily in this construction a piece may be added without actually being part of the door and this is particularly useful in cars built to carry very heavy loads.

In the operation of this invention the weight of the grain keeps the doors tightly to their position against the door posts and the angle ends of the hinged rods are behind the tracks and as soon as the car reaches its destination the locking pawl is removed from the top of the door in the manner described and the lower end of the door is pried upwardly to start the grain flowing. This soon relieves the weight of the grain behind the door so that a comparatively light shove will send the grain door to its position under the ceiling where it is locked by the upper dog, then the car can be dumped or unloaded in any way without affecting the door which is well out of the way and if desirable the car can be used for other purposes for the return journey and both doors remain to their locked position under the ceiling.

What I claim is:

1. A car door comprising a plurality of slats longitudinally hinged at the joints and operating as a roll door and hinge pins having double offsets at the ends forming tread members and hangers for the door in its sliding and stored positions, trackways secured over vertical recesses in door posts and therebeyond across the car under the ceiling and suspended therefrom.

2. A car door comprising a plurality of slats longitudinally hinged at the joints and operating as a roll door and hinge pins

having double offsets at the ends forming tread members and hangers for the door in its sliding and stored positions, a plurality of vertical wires secured to said door and connecting said hinge pins to one another, trackways secured over vertical recesses in door posts and therebeyond and across the car under the ceiling and suspended therefrom. 65

3. A car door comprising a plurality of slats longitudinally hinged at the joints and operating as a roll door and hinge pins having double offsets at the ends forming tread members and hangers for the door in its sliding and stored position, short vertical wire rods having eyes encircling said hinge pins and having other eyes secured to said door, trackways secured over vertical recesses in door posts and therebeyond and across the car under the ceiling and suspended therefrom. 75 80

4. A car door comprising a plurality of slats longitudinally hinged at the joints and operating as a roll door and hinge pins having double offsets at the ends forming tread members and hangers for the door in its sliding and stored positions, a slot in the lower exterior portion of said door having a metal angle bar, trackways secured over vertical recesses in door posts and therebeyond and across the car under the ceiling and suspended therefrom. 85 90

5. A car door comprising a plurality of slats longitudinally hinged at the joints and operating as a roll door and hinge pins having double offsets at the ends forming tread members and hangers for the door in its sliding and stored positions, a pawl having an L-shaped slot therein and adapted to engage said door in its operating position, trackways secured over vertical recesses in door posts and therebeyond and across the car under the ceiling and suspended therefrom. 95 100 105

6. A car door comprising a plurality of slats longitudinally hinged at the joints and operating as a roll door and hinge pins having double offsets at the ends forming tread members and hangers for the door in its sliding and stored positions, trackways secured over vertical recesses in door posts and therebeyond across the car under the ceiling and suspended therefrom, and a pawl secured to the upper portion of one of said door posts and having a finger adapted to engage with said door in its stored position. 110 115

Signed at Montreal, this 20th day of January, 1925.

JAMES OMAR OAKLEY.
